SWINGING DOOR

August O. Rapp, Lakeville, Minn.

Application May 8, 1939, Serial No. 272,522

1 Claim. (Cl. 20—16)

This invention relates to swinging doors and has for an object to provide a simplified hinge and operating means therefor, which will permit the door to be swung open from either of the side jambs of the door frame.

A further object is to provide, in a swinging door of this type, simplified latching mechanism for controlling the operating means to prevent the door from being opened from both of the side jambs at the same time.

A still further object is to provide a door of this character which will be formed of a few strong simple and durable parts, which will be inexpensive to manufacture and install and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification:

Figure 1 is a front elevation of a swinging door constructed in accordance with the invention, with portions broken away to expose the parts of the invention.

Figure 2 is a view similar to Figure 1 but showing the hinges on one side in separated condition to permit the door to be swung open from the opposite door jamb.

Figure 3 is a cross sectional view taken on the line 3—3 of Figure 1 showing one of the latches in released position.

Figure 4 is a cross sectional view taken on the line 4—4 of Figure 2 showing the latch in operative position.

Figure 5 is a longitudinal sectional view taken on the line 5—5 of Figure 1 showing the latch in released position.

Figure 6 is a longitudinal sectional view taken on the line 6—6 of Figure 2 showing the latch in operative position.

Figure 7 is a detail longitudinal sectional view taken on the line 7—7 of Figure 1 showing the handles and mutilated gear for operating the mechanism.

Referring now to the drawing in which like characters of reference designate similar parts in the various views, 10 designates side jambs of a door frame to each of which is secured hinge structures comprising a hinge plate 11, which is attached to the jamb by screws 12 and is pro-

vided with a hinge eye 13. There are four of these hinge structures, two on each jamb, duplicates of each other, for mounting the door 14 comprising the subject matter of this invention, to swing from either jamb. The door 14 is provided with four hinge structures complementary to those carried by the jamb and each comprising a plate 15 attached to the door by screws 16 and having aligned hinge eyes 17 which interfit with the single hinge eye 13 of the complementary 10 hinge plate 11 of the door jamb.

A pair of rack bars 18 are mounted to slide vertically in recesses 19 located at opposite sides of, and close to, the vertical center of the door. Horizontal arms 20 are carried by the upper and 15 lower ends of the rack bars and are provided with respective hinge pintles 21 which engage the hinge eyes 13 and 17 of respective hinge structures. Each pintle is withdrawn from the eye 13 carried by the door jamb when the respective 20 rack bar is moved upwardly but never leaves the upper hinge eye 17 of the companion hinge structure carried by the door. Thus the door is unhinged from one of the jambs to permit it to be swung open on the hinge structure on the 25 other jamb as will presently be described.

A mutilated gear 22 is mounted on a shaft 23 which extends through the door and projects from opposite sides thereof between the rack bars 18. Handles 24 are secured to the ends of the shaft. 30 The mutilated gear is provided at diametrically opposite points with teeth 25 which engage the teeth 26 of the rack bars. When the shaft 23 is turned in either direction, the mutilated gear will raise a corresponding one of the rack bars 18 as 35 best shown in Figure 2, to disconnect the hinge structures on one jamb of the frame and permit the door to be swung open on the hinge structures on the other jamb.

A leaf spring 27 is secured intermediate its ends 40 by a bolt 28 to the door and bears with its ends upon the rack bars 18. The spring is placed under tension as one of the rack bars is raised to return it to initial position, when the respective latch bar, about to be described, is released.

Each latch bar 29 is secured at the lower end to the door by screws 31 or similar connectors and is provided at the upper end with a laterally directed tip end 32, which is normally retracted within the door but when the latch is in operative 50 position projects from the door, as best shown in Figures 5 and 6. The latch is provided with a shoulder 30 intermediate its ends adapted to lodge underneath the upper horizontal arm 20 of a respective rack bar as shown in Figure 6 and 55

prevent the bar from returning to released position until the door is fully closed. Thus when the door is being closed, the tip end 32 contacts with the stop 33 of the door frame head 34 and pushes back the latch to disengage the shoulder 30 from underneath the raised horizontal arm 20 so that the latter may be moved to initial position by the spring 27 to permit the hinge pintles again connecting the hinge eyes of the disconnected hinge structures to hold the door closed.

From the above description it is thought that the construction and operation of the invention will be fully understood without further explanation.

What is claimed is:

The combination with a door and door frame having separable hinges and hinge pintles connected to the door and door frame at both sides 20 of the door, of a pair of rack bars disposed to slide vertically on opposite sides of and close to the vertical median line of the door, horizontal arms on the lower and upper ends of the rack

bars connected to respective lower and upper pintles of the separable hinges for unhinging the door from one side of the frame, a shaft projecting at both ends from the door between the rack bars, handles on the ends of the shaft, a gear fixed to the shaft having gear teeth at diametrically opposite points engaging respective rack bars, a leaf spring secured intermediate its ends to the door and bearing at the ends upon respective rack bars, and resilient latch bars secured to the upper portion of the door near respective hinges, said latch bars having shoulders adapted to lodge underneath respective upper horizontal arms, said latch bars terminating in laterally directed tip ends adapted to engage the conventional stop on the door frame and push back the latch bars to dislodge the latch bar shoulder from the respective horizontal arm and permit the arm being moved by said leaf spring to connect the disconnected hinges to normally hold the door closed.

AUGUST O. RAPP.
